R. COOPERSMITH

GARMENT

Filed May 3, 1924

INVENTOR:
Rudolph Coopersmith,
by Counsel,
His ATTORNEYS.

UNITED STATES PATENT OFFICE

RUDOLPH COOPERSMITH, OF ST. LOUIS, MISSOURI.

GARMENT.

Application filed May 3, 1924. Serial No. 710,713.

To all whom it may concern:

Be it known that I, RUDOLPH COOPERSMITH, a citizen of the United States, and a resident of the city of St. Louis, in the State of Missouri, have invented a new and useful Improvement in Garments, of which the following is a specification.

This invention relates to garments and more particularly to body-garments of the kind known as shirts and shirt-waists for men's and women's wear, respectively.

The principal object of the present invention is to provide an improved construction in such garments that will overcome the tendency of the garment to creep upward on the wearer and become displaced or wrinkled. Another object is to adapt the retaining means for adjustment to the waist of the wearer. Other objects are neatness of appearance and simplicity and cheapness of construction.

The invention consists in the means hereinafter set forth for attaining the above objects; and it also consists in the parts and in the arrangements and combinations of parts hereinafter described and claimed.

The accompanying drawing, which forms part of this specification and wherein like symbols refer to like parts wherever they occur, is a front view of a shirt embodying my invention, portions of the shirt being folded back to disclose the retaining device.

Referring to the accompanying drawing, my invention is shown in connection with a body-garment in the form of an ordinary coat-shirt 1 for men's wear.

The retaining device comprises intermediate and end pieces of cloth or other suitable material which are sewed or otherwise fastened to the inside of the shirt at the waist-line thereof, and serve to reinforce said shirt along said line. The intermediate strip 2 is secured to the back of the shirt; and the end strips 3 are secured to the front portions thereof with their outer end portions left loose. The end and intermediate strips are disposed end to end along the waist-line of the shirt with their adjacent ends spaced apart; and said adjacent ends of said intermediate and end strips are connected together by means of strips of elastic 4 which cooperate with the non-elastic strips to form a belt or waistband. The loose or free outer end portion of one of the end strips is provided with a series of buttons 5; and the loose or free outer end portion of

the other end strip is provided with buttonholes 6 adapted to receive said buttons 5, whereby the loose or free outer ends of the end strips are adapted to be lapped and joined together when the shirt is buttoned up.

The adjacent end portions of the intermediate and end strips are provided with a series of buttonholes 7 adapted to receive buttons 8 that are secured to the ends of the elastic strips 4, whereby said elastic strips may be replaced when they lose their elasticity or removed before the shirt is laundered. The middle portions of the elastic strips 4 are loosely held in position by means of cloth straps 9 that are sewed or otherwise fastened to inside of the shirt midway between the adjacent ends of the intermediate and end strips and serve as guides for said elastic strips.

In use, the free outer ends of the end strips of the retaining device are lapped and buttoned together. The shirt is then buttoned up, thereby entirely concealing the retaining device. In the buttoned position of the retaining belt, the elastic sections thereof operate to maintain a yielding tension of the belt around the waist of the wearer, whereby the waist portion of the shirt is drawn snugly about the waist of the wearer. This snug fit of the shirt about the waist of the wearer serves to hold the shirt in proper position at the waist line, thereby preventing creeping or sliding movement of the body portion of the shirt, which movement tends to cause portions of the shirt to become wrinkled or displaced.

Some of the important advantages of my retaining device are, namely: It permits the elastic strips to be raised or lowered for long or short-waisted persons; it provides for variation in the waist size; it enables the elastic strip to be readily replaced when worn and removed before laundering; it strengthens or reinforces the waist portion of the shirt; and it is entirely concealed and is of simple and cheap construction.

Obviously, the device admits of considerable modification without departing from the invention. Therefore, I do not wish to be limited to the precise construction shown and described.

What I claim is:

1. The combination of a garment of the kind described and a retaining device therefor, said device comprising a strip located

entirely within and removably secured to said garment along its waist portion, said garment and said strip being provided with co-operating fastening devices adapted to 5 permit vertical adjustment of said strip with relation to said garment, said fastening devices being adapted to prevent horizontal movement of said strip with relation to said garment.

10 2. The combination of a garment of the kind described and a retaining device therefor, said device comprising elastic strips located entirely within and removably secured end to end to the inside of said garment along the waist portion thereof, said garment and said strips being provided with co-operating fastening devices adapted to permit vertical adjustment of said strips with relation to said garment, said fastening devices being adapted to prevent horizontal movement of said strips with relation to said garment.

3. The combination of a garment of the kind described and a retaining device therefor, said device comprising intermediate and end sections permanently secured to the inside of said garment along its waist portion, the outer ends of said end sections being left loose and formed with cooperating fastening devices, whereby said ends are adapted to be joined together, and elastic sections connecting the adjacent ends of said end and intermediate sections.

4. The combination of a garment of the kind described and a retaining device therefor, said device comprising non-elastic intermediate and end sections permanently secured end to end to the inside of said garment along its waist portion, the outer ends of said end sections being left loose and formed with cooperating fastening devices, whereby said ends are adapted to be lapped and joined together, and detachable elastic sections connecting the adjacent ends of said end and intermediate sections.

5. The combination of a garment of the kind described and a retaining device therefor, said device comprising an intermediate section secured to the inside of said garment at the back thereof, end sections secured to the inside of said garment on opposite sides of the opening in the front thereof, said sections being disposed end to end along the waist line of said garment, the outer ends of said end sections being provided with cooperating fastening devices, whereby said ends are adapted to be joined together, and elastic sections connecting the adjacent ends of said intermediate and end sections.

6. The combination of a garment of the kind described and a retaining device therefor, said device comprising an intermediate

scction secured to the inside of said garment at the back thereof, end sections secured to the inside of said garment on opposite sides of the opening in the front thereof, said sections being disposed end to end along the waist line of said garment with their adjacent ends spaced apart, the outer ends of said end sections being provided with co-operating fastening devices whereby said ends are adapted to be lapped and joined together, and elastic sections connecting the adjacent ends of said intermediate end sections, said elastic sections being detachably secured to said end and intermediate sections. 65 70 75

7. The combination of a garment of the kind described and a retaining device therefor, said device comprising an intermediate section secured to the inside of said garment at the back thereof, end sections secured to the inside of said garment on opposite sides of the opening in the front thereof, said sections being disposed end to end along the waist line of said garment with their adjacent ends spaced apart, the outer ends of said end sections being provided with cooperating fastening devices whereby said ends are adapted to be detachably secured together, elastic strips connecting the adjacent ends of said intermediate and end sections, said elastic strips being detachably secured to said end and intermediate sections and means whereby said elastic strips are adapted to be adjusted vertically with relation to the end and intermediate strips.

8. The combination of a garment of the kind described and a retaining device therefor, said device comprising a non-elastic intermediate section permanently secured to the inside of said garment at the back thereof, non-elastic end sections permanently secured to the inside of said garment on opposite sides of the opening in the front thereof, said sections being disposed end to end along the waist line of said garment with their adjacent ends spaced apart, elastic sections connecting the adjacent ends of said intermediate and end sections, straps secured to the inside of the garment between the adjacent ends of said intermediate and end sections for holding said elastic sections in position, means on the outer ends of said end sections whereby said ends are adapted to be fastened together, means for removably securing said elastic sections to said intermediate and end sections, and means permitting vertical adjustment of said elastic sections with relation to said end and intermediate sections.

Signed at St. Louis, Missouri, this 29th day of April, 1924.

RUDOLPH COOPERSMITH.
